UNITED STATES PATENT OFFICE.

WILLIAM P. CLIFFORD, OF MORAVIA, IOWA.

ORE SEPARATING AND CONCENTRATING MACHINE.

No. 895,725.

Specification of Letters Patent.

Patented Aug. 11, 1908.

Application filed September 21, 1907. Serial No. 393,933.

To all whom it may concern:

Be it known that I, WILLIAM P. CLIFFORD, a citizen of the United States, residing at Moravia, in the county of Appanoose and State of Iowa, have invented certain new and useful Improvements in Ore Separating and Concentrating Machines, of which the following is a specification.

My invention relates to improvements in ore-separating and concentrating machines, the invention being specially designed for use in the treatment of very fine ores and mineral dust, sands, etc., in extracting or separating flake and flour gold, silver etc.

15 The invention belongs to that class or type of machines in which the valuable particles of the crushed or reduced ore are concentrated into as small a bulk as is economically advantageous by the fall of the particles in air currents. This concentration of particles is generally brought about by the fall of the particles in water; but, as is well known, by this process the concentration depends upon the difference in specific gravity of the valuable 20 ore and the waste vein stone or rock.

The smaller particles of ore are separated by a variety of machines. The action of many of them is based upon the behavior of particles carried down an inclined plane by a 30 thin stream of water. If the gradient of the plane and the strength of the thin current are properly arranged, the denser particles will be deposited and the specifically lighter ones washed away, although they may be 35 equal-falling if allowed to settle in deep water.

The paramount object of this invention is to overcome many of the difficulties experienced in concentrating in water, and to produce a generally-improved ore-separating 40 and concentrating machine for the treatment of very fine ores, practically saving all fine ores and mineral dust heretofore washed away in treating by the water process, or by improper air blasts; or air currents impro- 45 erly applied in machines of this class.

With these and other ends in view, the invention consists in the novel construction, arrangement and combination of parts, hereinafter described, illustrated in the accompanying drawings, and particularly pointed out in the appended claims.

Referring to the drawings, forming a part of this specification, Figure 1, is a side elevation of a machine, constructed in accordance 50 with my invention, a portion of its side wall being broken away for the purpose of clearer

illustration of its parts. Fig. 2, a horizontal sectional view, taken through line 2—2, of Fig. 1, a portion of the suction-fan-casing being broken away to show the suction-fan. 60 Fig. 3, a vertical sectional view of the sizing-reel, and feed end of the machine, taken through line 3—3, of Fig. 2. Fig. 4, a perspective view of one of the revoluble mineral-dust-catching plate-armed reels or winged-wheels. Fig. 5, a perspective view of the revoluble sizing-reel. Fig. 6, a perspective view of the revoluble fluted feeding-roll.

Similar characters of reference designate like parts throughout all the figures of the 70 drawings.

The improved machine comprises a supporting-frame consisting of base-beams 1, side-beams 2, and uprights 3, for supporting the walls of the various suction-trunks and 75 housings of the machine.

The front or receiving end of the machine is provided with a sizing-reel-housing 4, and the rear or fan end of the machine is provided with a suction-fan-housing 5, and a plurality 80 of suction-trunks 6, are provided, preferably three in number as shown, and graded, and decreasing in size and capacity from front to rear, the first being adapted as a separator for the coarse ore, the second for the medium 85 ore, and the third for the fine ore.

The several trunks 6, are provided at their front or receiving ends with vertically-arranged suction-pipes 7, and are brought into communication with the suction-fan 8, at the 90 rear, by means of horizontal longitudinally-extending suction-air passages 9, terminating in a common or main exhaust fan-chamber 10, above the fan-housing 5. The suction-trunks 6, are also provided with depending-portions 11, provided with downwardly and rearwardly-extending chutes 12, adapted to convey material to the exit-openings 13, in their lower ends, the first two depositing material into receiving hoppers 14, fixed 100 to the front ends of the adjacent suction-pipes 7, and communicating therewith. The last or rear exit-opening 13, is adapted to deposit tailings, while the first, second and third suction-pipe exits are adapted to deposit coarse, medium fine, and fine pure ores, respectively, as the material is carried by the suction air currents through the several suction-air passages or trunks.

The several suction-trunks 6, with the suction-pipes 7, and air passages 9, are preferably divided into three longitudinally-ex-

tending sections or divisions 15, 16, and 17, by means of partition or division-walls 18, extending lengthwise of the machine. The divisions or passages 15, 16, and 17, are 5 adapted to receive the fine, medium fine, and coarse ore or material, respectively, as received from the sizing-reel, hereinafter described.

Transverse deflector-boards or plates 19, 10 are mounted in the trunks 6, preferably parallel with the chutes 12, and are adapted to deflect the air currents, with floating or suspended material, downwardly into the depending portions 11, and thence upwardly 15 into the horizontal air passages 9.

As a means of catching all the fine particles of material, such as flour or flake gold and silver, plate-armed wheels or reels 20, are mounted, just in front of the deflector- 20 boards or plates 19, and at the rear of the horizontal air-passages 9, in such a manner that the radial plate-arms 21, will project into or intersect the air-currents passing from the trunks 6, into the said horizontal 25 passages 9. The radial plate-arms or wings 21, are covered with quick-silver by means of a suitable adhesive or binding agent, or they may carry separate removable quick-silver plates 22, as shown in Fig. 4, of the drawings. 30 As the air current, carrying the fine particles of material, strikes the arms or wings 21, the wheels 20, are revolved, and in so doing the quick-silver arms or plates are dipped into the current, thus causing all fine particles of 35 mineral such as flour and flake gold and silver to come into engagement with and adhere to the quick-silver.

When the arms or wings 21, or plates 22, as the case may be, are loaded or covered to 40 their normal carrying capacity, the wheels 20, or the plates 22, may be taken out and the adhering particles of mineral removed.

Valves 23, are pivotally and adjustably-mounted in the horizontal passages 9, and 45 are adapted to be adjusted therein whereby to increase or decrease the force of the air currents to provide for the various ores and the desired concentrations thereof.

The crushed or disintegrated ore is 50 contained in the hopper 24, and is conveyed to the sizing-reel through the medium of the feed-pipe 25, having its discharge end taking into the elevated or receiving end of the revolute sizing-reel 26, preferably above the 55 axis or driving-shaft 27, thereof, as shown. If desired, a gate-valve 28, may be mounted in the feed-pipe 25, to control the feed of the ore to the sizing-reel.

The sizing-reel 26, is inclined and has its 60 ends projecting through openings 29, in the sides of the housing 4. The driving-shaft 27, is mounted in bearings 30, secured to depending bearing-supporting-arms 31, carried upon the ends of the cross-arm 32, mounted 65 on the housing 4.

The driving-shaft 27, is adapted to be driven by means of a drive-pulley 33, provided with a belting 34, passing over a pulley 35, on the fan-shaft 36. The fan-shaft 36, is driven by means of a main driving-pulley 37, communicating with any suitable 70 source of power.

The periphery of the sizing-reel 26, is preferably octagonal in outline and is divided into sections 38, 39, and 40, corresponding 75 in width to the width of the sections 15, 16, and 17, of the trunks, and adapted to separate the material into fine, medium fine, and coarse particles as shown by the meshes of the wire covering in Fig. 4. If desired, 80 sheet-metal may be substituted for the wire covering and provided with perforations corresponding with the meshes of the wire covering.

The receiving end of the sizing-reel 26, is 85 preferably provided with a peripheral flanged head or band 41, to prevent any overflow or spilling of material as received from the feed-pipe 25.

The periphery of the reel 26, may be made 90 up of a continuous endless covering as shown in Fig. 4; or the sides or planes may be made up of a series of longitudinally-extending frames 42, covered with foraminous material, the contiguous or abutting sides of the 95 frames 42, resting upon and being secured to the longitudinal bars 43, by means of turn buttons 44, as shown in Figs. 1, and 3.

The material passing through the periphery of the sizing-reel 26, falls upon the inclined chute 45, and is fed into the first vertical suction-pipe 7, of the first or front suction-trunk 6, by means of a fluted feeding-roll 46, mounted in suitable bearings 47, extending into the lower or feeding portion of 100 the housing 4, and suction-pipe 7, through 105 slots 47, formed therein.

The feeding-roll 46, is revolved by means of a cone-pulley 47^a, receiving motion from a second pulley 48, on the sizing-reel shaft 27, by means of a belting 49. The speed of the feeding-roll 26, is regulated by shifting the belting 49, thus also regulating the feed of the material, and the feed of the material is further regulated by means of a pivotally-mounted depending bank-valve 50, normally closing the slot 47, of the suction-pipe 7, and impinging against the feeding-roll 46, by means of a horizontal lever-arm 51, carrying an adjustably-mounted weight 52. 115

The revolution of the wheels 20, and the condition of the plate-arms 21, may be observed through the glass covered sight-openings 53, arranged on each side of the 120 wheels 20.

From the foregoing description, taken in connection with the accompanying drawings, the operation and advantages of my 125 invention will be readily understood.

Having thus described my invention, 133

without having attempted to set forth all the forms in which it may be made, or all the modes of its use; I declare that what I claim and desire to secure by Letters Patent, is,—

- without having attempted to set forth all the forms in which it may be made, or all the modes of its use, I declare that what I claim and desire to secure by Letters Patent, is,—

5 1. An ore-separating and concentrating machine, comprising a sizing-reel and housing, a suction-fan and housing, a plurality of suction-trunks arranged in echelon and provided with horizontal air passages leading to

10 said suction-fan, transverse deflector-plates mounted in said trunks and adapted to divert air-currents downwardly into the lower portions of said trunks and thence upwardly to the intake ends of said horizontal air-passages, and reels provided with plate-arms arranged to take into said air-currents whereby said reels are revolved and said air-currents are intercepted by the dipping in of said plate-arms.

15 2. In an ore separating and concentrating machine, the combination with a suction-trunk provided with an intake and a downwardly-diverted outlet passage, and a deflector-plate mounted in said downwardly-diverted outlet passage; of a quick-silver plate-armed wheel mounted at the return portion of said downwardly-diverted outlet passage and taking into and revolved by the air-current passing from said deflector-plate.

20 3. In an ore-separating and concentrating machine, a suction-trunk provided with a deflector-plate and a depending portion beneath said deflector-plate; of an armed wheel or reel mounted in and revolved by the return air-current diverted into said depending portion of said trunk by said deflector-plate.

25 4. An ore-separating and concentrating machine, comprising a sizing-reel and housing, a suction-fan and housing, a plurality of longitudinally - divided suction - trunks arranged in echelon intermediate said housings and each provided with a vertically-arranged suction-pipe at its front and a horizontal outlet passage leading to said suction-fan, a depending portion formed intermediate said suction-pipe and outlet passage and provided with a downwardly and rearwardly-inclined chute terminating in an exit-opening, and a

30 valve pivotally and adjustably-mounted in said outlet-passage.

35 5. In an ore-separating and concentrating machine, the combination with a sizing-reel and housing provided with a feeding-roll and

35 bank-valve, a suction-fan and housing, a longitudinally-divided suction-trunk provided with a vertical suction-pipe intersected by said feeding-roll, and a longitudinal air-passage communicating with said suction-fan and housing; of a deflector-plate mounted in said suction-trunk and providing an air-passage downwardly into said suction-trunk from the top of said suction-pipe, a reel provided with quick-silver covered radially-extending plates revolvably-extending into the air-currents passing from said air-passage provided by said deflector-plate to said longitudinal air-passage, and a valve mounted in said longitudinal air-passage whereby to regulate the force of said air-currents.

40 6. In an ore-separating and concentrating-machine, a sizing-reel and housing, a suction-fan and housing, a suction-trunk intermediate said housings and provided with a vertically-arranged suction-pipe and a longitudinally-extending air-passage having a depending portion, a deflector-plate diverting the air-currents downwardly into said depending portion, and a winged-wheel mounted in and revolved by the return air-currents passing from said depending portion.

45 7. In an ore-separating and concentrating-machine, a plurality of suction-trunks arranged in echelon and each provided with a vertically-arranged suction-pipe and a horizontal outlet-passage having a depending portion, a deflector-plate in said outlet-passage and diverting the air-currents into said depending portion, and winged-wheels revolvably-mounted in the return of said air-currents to said outlet-passage.

50 8. In an ore-separating and concentrating-machine, a plurality of longitudinally-divided suction-trunks arranged in echelon and each provided with a vertically-arranged suction-pipe, a horizontal outlet-passage, and a depending portion; a deflector-plate diverting the air-currents into said depending portion, and reels provided with arms intercepting the return of said air-currents from said depending portion.

55 In testimony whereof I have affixed my signature, in presence of two witnesses.
